UNITED STATES PATENT OFFICE

122,573

DESIGN FOR A TOY GOLF GAME DEVICE

Donna McDonald, Los Angeles, Calif.

Application December 18, 1939, Serial No. 88,981

Term of patent 3½ years

To all whom it may concern:

Be it known that I, Donna McDonald, a citizen of the United States, residing at 5009 Franklin Avenue, in the city of Los Angeles, in the county of Los Angeles and State of California, have invented a new, original, and ornamental Design for a Toy Golf Game Device, of which the following is a specification, reference being had to the accompanying drawing, forming part thereof, in which:

Fig. 1 is a front elevational view of a toy golf game device, showing my new design; and Fig. 2 is a top plan view thereof.

I claim:

The ornamental design for a toy golf game device, as shown.

DONNA McDONALD.
